SUCKER ROD SAND TRAP

Wilfred S. Crake, Kilgore, Tex., assignor to Shell Development Company, Emeryville, Calif., a corporation of Delaware

Application May 24, 1952, Serial No. 289,813

7 Claims. (Cl. 103—220)

1

This invention relates to well production equipment and pertains more particularly to apparatus adapted to prevent or minimize the settling of sand within a well which is being produced by reciprocating a sucker rod pump.

In some oil fields varying quantities of sand are pumped to the surface along with the oil. Frequently, a well prime mover which reciprocates the pump may stop due to breakdown of some part of the equipment. In other instances the well prime mover may be automatically or manually stopped periodically on a set time schedule when the well is being produced by intermittent pumping. For example, in wells where the capacity of the pump is greater than the amount of oil flowing from the oil-bearing formation into the well borehole, the well pumping installation may be shut off for predetermined periods, say 12 hours out of every day.

When the well pumping installation is stopped, the sand carried in suspension by the column of oil in the production string settles to the bottom of the well and piles upon the top of the pump plunger and clogs the valves. This causes "sanding up" of the pump which often requires the removal of the pump plunger for repairs.

It is the primary object of the present invention to provide relatively simple and inexpensive sand-trapping apparatus adapted to be positioned in an oil production tubing string above a reciprocating well pump for preventing sand from settling on the pump when the pump is not operating.

Another object of this invention is to provide sand catching apparatus which may be easily installed along a string of sucker rods above a plunger-type pump within a well borehole for catching sand at different levels as it settles out of the column of oil above the pump when the pump is not operating.

A further object of this invention is to provide simple and effective sand-trapping apparatus adapted to be secured to a sucker rod string in the production tubing above a reciprocating well pump for effectively closing the production tubing at varying levels when the pump is not operating, said apparatus at the same time being adapted to open the tubing and allow oil to be produced therethrough when the pump is operating.

Another object of the present invention is to provide a sand-trapping device adapted to be mounted on a sucker rod string within a well production tubing to form a substantially horizontal barrier within the production tubing upon

2

which sand may settle when the well is not pumping, there being a seal formed between the sand-trapping barrier and the production tubing, which seal becomes more positive as greater quantities of sand settle thereon.

These and other objects of this invention will be understood from the following description taken with reference to the drawings, wherein:

Figures 1 and 6 are longitudinal views, partly in cross-section, of the present sand-trapping apparatus mounted on a sucker rod string above a reciprocating well pump in a string of production tubing.

Figures 2, 3 and 4 are diagrammatic views of the present sand-trapping apparatus during various phases of well production operations.

Figure 5 is a view, partly in cross section, of the present sand-trapping apparatus having a semi-rigid type construction.

Referring to Figure 1 of the drawing, a production or pump tubing 11 is shown vertically positioned in a manner similar to its position in the well casing or borehole of an oil well which is produced by a well pump of the reciprocating type.

The top of the pump plunger unit 12, which forms the valve cage for a traveling ball valve 13 and is retractable within the production tubing 11, is shown as being secured to the lower end of a sucker rod string 14 which is suspended within the tubing 11 from a pumping mechanism (not shown) located at the surface by the wellhead.

Secured to the sucker rod string 14 above the pump plunger unit 12 are one or more sand-trapping barriers 15 which are made of a flexible material such as rubber, synthetic rubber, rubberized canvas or various plastic materials. Preferably, an oil-resistant material is employed thus reducing the rate at which the barriers deteriorate and become worn out.

Each sand-trapping barrier 15 is a substantially flat flexible disc, preferably having a concave upper face 16 or formed in a concave section, as illustrated in Figure 1.

Secured to or integrally formed on the bottom of the disc 15 is a short cylindrical section 17 which is preferably made of the same flexible material as the disc 15. An axial hole 18 is provided in the disc 15 and cylindrical section 17 through which a sucker rod 14 extends. The diameter of the hole 18 in the disc 15 is slightly smaller than the diameter of the sucker rod so that the throat of the disc 15 formed by the cylindrical section 17 clamps on the sucker rod 14.

in elastic tension to hold the disc 15 fixedly positioned on said rod 14. The cylindrical throat section 17 has sufficient gripping power to hold the disc 15 in place during the reciprocation of the sucker rod string.

The sand-trapping disc 15 is of a diameter substantially equal to or slightly larger than the inside diameter of the production tubing 11. The disc thickness is determined by the strength of the disc material and the diameter of the tubing string 11, the thickness being sufficient to support a substantial quantity of sand which settles on the disc 15 in its stationary position. One advantage of employing a disc 15 having a concave upper surface, as shown, is that increasing amounts of sand settling on the top of the disc 15 weigh and depress the outer edge of the disc slightly down so that it is pressed tightly against the inner wall of the tubing string 11 thus preventing any sand from falling past.

In some pumping installations a sand-trapping disc 20, shown in dotted outline, may be employed having a flat or horizontal upper surface. Discs 20 of this structure are preferably of a diameter which is slightly greater than the inner diameter of the tubing string 11.

Installation of a sucker rod string of a sand-trapping barrier comprising disc 15 and throat section 17 is accomplished by stretching the disc radially whereby the hole 18 therethrough is enlarged so that the barrier may be forced over the coupling and upset 21 of the sucker rod 14.

It is realized that the present sand-trapping barriers may be constructed of a separate flexible disc 22 (Figure 5) fixedly secured to a rigid collar 23 which is either permanently or removably secured to a sucker rod 14 as by welding or bolting. The disc 22 is secured to the top of the collar 23 by any suitable means, as by a holding ring 24 and bolts 25. The rigid collar 23 may be of split ring construction fastened together by bolts 26 to facilitate its installation on the sucker rod string.

Preferably, the sucker rod string 14 is equipped with a plurality of centering guides which comprise a cylindrical body member 28 having three or more radially extending guide plates 29 integrally formed thereon or affixed thereto, as by welding. The upper and lower ends, 30 and 31 respectively of the body member 28 may be threaded for connection between the ends 21 and 32 of two sucker rods. The sand-trapping discs 15 are preferably secured to the sucker rod string 14 near the centering guides 28-29 so as to minimize the wear due to frictional contact between the discs 15 and the inner wall of the production tubing string 11. The plates 29 of the centering guide extend radially over a distance slightly less than the inside diameter of the production string 11 so that the centering guide may freely move axially within the tubing string while maintaining the sucker rod string 14 substantially in the center of the tubing.

The discs 15 are also preferably secured to the sucker rod string 14 just above a tool joint 19 or 32 or just above a centering guide which is threadedly connected into the sucker rod string. Thus, sand accumulates on the disc and piles up around the smooth portion of the rod, or that portion having the smallest diameter, rather than around a tool joint, thereby reducing the hazard of sticking. If desired, a sand-trapping disc 40 may be attached directly to body member 28 of the centering guide rather than to the sucker rod string 14.

In operation, when the pumping installation is shut down the sucker rod string 14 is not reciprocating, the sand-trapping disc remains stationary, as shown in Figure 1, and any sand being carried by the production fluid settles in a pile 35 on top of the disc. The same action takes place at each disc which is secured to the sucker rod string with the sand carried by the well fluid between any two discs settling out on the lower disc.

When the pump is started again the agitation of the oil in the tubing string due to reciprocation of the sucker rod string 14 and the attached discs 15 causes the sand which has accumulated on the discs to be swept off and again suspended in the stream of well fluid as it is pumped upward and out of the well. Since the well fluid both above and below each disc 15 moves upward during the upstroke of the pump, the disc 15 maintains its normal unflexed position, as shown in Figure 2, with the outer edge of the disc touching or in substantial contact with the inner wall of the tubing string 11.

On the downstroke of the pump the outer edge 25 of each disc 15 is flexed upwardly and inwardly by the force of the well fluid passing up the tubing string 11 through the annular space between the inner wall of the tubing string and the outer edge of each disc as shown in Figure 3. This 30 action is repeated throughout the pumping operation.

When the sucker rod string 11 is withdrawn from the well for repairs or other reasons, the discs 15 are sufficiently flexible so that the speed 35 of withdrawal may be sufficient to cause the fluid force acting on the upper surface of each disc to flex the disc downwardly, as shown in Figure 4, thus forming a sufficient annular space between the disc and the tubing wall through which the 40 well fluid may pass.

I claim as my invention:

1. In a well pumping installation comprising a production tubing suspended in the well for conveying well fluid to the surface and a reciprocating-type well pump positioned in the lower end of tubing, the combination of a sucker rod string suspended within the production tubing, the lower end of said sucker rod string being affixed to the pump for reciprocating said pump in a vertical plane, and sand-trapping means secured to the sucker rod string above said well pump for catching sand settling in the tubing when the pump is not reciprocating, said sand-trapping means comprising substantially flat flexible disc means having an axial hole therethrough in which the sucker rod string may be positioned, said disc means extending transversely in said tubing and having a diameter substantially equal to the inner diameter of said tubing.

2. In a well pumping installation comprising a production tubing suspended in the well for conveying well fluid to the surface and a reciprocating-type well pump positioned in the lower end of tubing, the combination of a sucker rod string suspended within the production tubing, the lower end of said sucker rod string being affixed to the pump for reciprocating said pump in a vertical plane, and sand-trapping means secured to the sucker rod string above said well pump for catching sand settling in the tubing when the pump is not reciprocating, said sand-trapping means comprising substantially flat flexible disc means, a short cylindrical throat section secured to one side of said disc means, 65 said disc means and cylindrical section having an

axial hole therethrough in which the sucker rod string may be positioned, said disc means extending transversely in said tubing and having a diameter substantially equal to the inner diameter of said tubing.

3. Sand-trapping apparatus for use in a production tubing of an oil well produced by reciprocating a pump at the end of a sucker rod string, said apparatus comprising substantially flat flexible disc means having a diameter substantially equal to the inner diameter of the production tubing, and means for securing said disc means to the sucker rod string whereby said disc means extends transversely within said tubing to form a seal thereacross adapted to catch sand which settles from the well fluid within the tubing when the sucker rod is not reciprocating.

4. Sand-trapping apparatus for use in a production tubing of an oil well produced by reciprocating a pump at the end of a sucker rod string, said apparatus comprising a plurality of substantially flat flexible discs of a diameter substantially equal to the inner diameter of the production tubing, and means for securing said discs in spaced relationship on the sucker rod string whereby said discs extend transversely within said tubing to form a seal thereacross adapted to catch sand which settles from the well fluid within the tubing when the sucker rod is not reciprocating, the outer edges of said discs flexing upwardly and inwardly on each down-stroke of the pump to permit the passage of well fluid thereby.

5. In a well pump installation, the combination of a tubing string, a sucker rod string reciprocable therein, and a plurality of essentially flat disc shaped elements mounted on the sucker string transversely thereto and substantially spaced from each other, the diameter of said disc elements being slightly in excess of the internal diameter of the tubing string, and the vertical cross-section of said disc elements being attenuated away from the axis thereof, whereby the rim of each disc element is readily deflected upwards upon a downward motion, and downwards

45

upon an upward motion of the sucker rod string by friction with the tubing string walls.

6. In a well pump installation, the combination of a tubing string, a sucker rod string reciprocable therein, and a plurality of flexible disc-shaped elements mounted on the sucker string transversely thereto and substantially spaced from each other, said disc elements being formed with a concave upper face to support sand settling in said tubing string, the diameter of said disc elements being slightly in excess of the internal diameter of the tubing string, and the vertical cross-section of said disc elements being attenuated away from the axis thereof, whereby the rim of each disc element is readily deflected upwards upon a downward motion, and downwards upon an upward motion of the sucker rod string by friction with the tubing string walls.

7. In a well pump installation, the combination of a tubing string, a sucker rod string reciprocable therein, centering guides affixed to said sucker rod string in vertical spaced relationship, and a plurality of flexible disc-shaped elements mounted adjacent said centering guides on the sucker string transversely thereto and substantially spaced from each other, said disc elements being formed with a concave upper face to support sand settling in said tubing string, the diameter of said disc elements being slightly in excess of the internal diameter of the tubing string, and the vertical cross-section of said disc elements being attenuated away from the axis thereof, whereby the rim of each disc element is readily deflected upwards upon a downward motion, and downwards upon an upward motion of the sucker rod string by friction with the tubing string walls.
